UNITED STATES PATENT OFFICE

117,949

DESIGN FOR A STOVE

Ira J. Golden, Searcy, Ark.

Application September 19, 1939, Serial No. 87,291

Term of patent 14 years

To all whom it may concern:

Be it known that I, Ira J. Golden, a citizen of the United States, residing at Searcy, in the county of White and State of Arkansas, have invented a new, original, and ornamental Design for Stoves, of which the following is a specification, reference being had to the accompanying drawing, forming part thereof.

Figure 1 is a front elevational view of a stove showing my new design.

Figure 2 is a right hand side elevational view thereof.

Figure 3 is a top plan view.

I claim:

The ornamental design for a stove, as shown.

IRAJ. GOLDEN.
